UNITED STATES PATENT OFFICE

WALTER H. KIRKBRIDE, OF SAN FRANCISCO, CALIFORNIA

RAILWAY-TRACK CONSTRUCTION

Application filed August 4, 1930. Serial No. 472,897.

My invention relates to that feature of railway-track construction which concerns the connection of the adjacent ends of the aligned rails; and it consists primarily in the employment and relative distribution of two kinds of joints, the nature of which may, in the first instance, be distinguished one from the other, by the comprehensive expressions "permanent" as applied to one, and "detachable" as applied to the other, these terms being understood in their common acceptation, signifying relativity of purpose and convenience.

The invention also consists, in its more limited aspect, of the novel relative distribution of said joints, as well as in such specific features as are found best adapted to the end sought; which end may be briefly stated to be reduction of expense of maintenance by minimizing wear at joints.

The nature of my said invention and the manner in which it is applied in track-construction will be ascertained in and by the following description taken in connection with the accompanying drawings in which the improvement is illustrated in its preferred form, though it is to be understood that changes may be made therein without departing from the spirit of the invention as defined by the claims hereunto appended.

In the drawings, Fig. 1 is a plan view, broken, of a railway-track in which my improved construction is embodied.

Fig. 2 is a plan view, enlarged, showing a permanent joint between the adjacent ends of aligned rails.

Fig. 3 is a plan view, enlarged, showing the adjacent ends of two rails separated laterally for the sake of illustration, to which said ends the members of a detachable joint are fitted, ready to be completed when the two rails are aligned.

Referring to Fig. 1, the numeral 1 indicates the cross-ties, and 2 are the rails of a railway track. At "A" are indicated the "detachable" joints, and at "B" are indicated the "permanent" joints. These are distributed in each line of rails of the track alternately, and this order in one rail line is in staggered relation to a similar order in the other rail

line. Thus each rail line is composed of units comprising two rails joined permanently, which units are themselves connected by detachable joints; and this system or order in the two rail-lines is, due to the track laying custom, necessarily in staggered relation.

By this distribution of these two kinds of joints, it will be seen that one desirable result is reached, to wit, that even though two lengths of rail are permanently connected and must thereafter, in maintenance work, be handled at a unit, such contingency is not prohibitive, for the track may still be taken apart by separating its permanently joined units at the detachable joints. And, moreover, as there is no joint wear at the permanent joints, the expense of maintenance is minimized in proportion to the number of said permanent joints, which in itself represents a one-half saving.

These permanent joints may be of any suitable nature; in practise, some form of welded joint. I have indicated such a joint in Fig. 2, in which the joint bars or fish-plates 3, which may be of any approved type, are welded below to the rail base at 4, and are welded under the head of the rail at 5, the weld crossing the line between the adjacent rail ends, and the heads of said rail ends are themselves welded together at 6. Any other form of welded joint may be used, since the sole requirement is permanency in the sense herein used.

The detachable joints "A" are, however, of special character, adapted for a further minimizing of maintenance expense. This will become apparent by reference to Fig. 3 in which the nature of this joint is illustrated. One of the joint bars or fish plates 7, which bars or plates may be of any suitable type, is permanently connected for half its length by welds suitably disposed, as, for example, along lines such as 8 and 9, to one of the rails, and the other bar or plate is similarly welded to the other rail. The other half of each bar or plate, projecting from its rail is detachably connected with the other rail by bolts 10. Thus the two rails can be readily separated, and since the welded half of each bar or plate is not subject to wear, the ex-

pense of maintenance is confined to the bolted half. The saving, at this point, represents another quarter, the total minimizing being a saving of three fourths as compared with practise.

5 I claim:

1. In railway-track construction, the combination of alternating permanent, and detachable rail-joints.
- 10 2. In railway-track construction, the combination of spaced parallel lines of rail; and alternating permanent, and detachable rail-joints, the alternation in one rail line being in staggered relation to that of the other rail line.
- 15 3. In railway-track construction, the combination of alternating fully permanent rail-joints with detachable partially permanent rail-joints.
- 20 4. In railway-track construction, the combination of permanent rail joints, with other rail joints alternating therewith and comprising a pair of joint-members crossing the line of rail separation, one portion of each member being permanently united to its respective rail and its other portion detachably connected with the other rail.
- 25 5. In railway-track construction, a rail-joint comprising a pair of joint members crossing the line of rail separation on opposite sides, one portion of each member being permanently united to its respective rail and its other portion detachably connected with the other rail.
- 30 35 In testimony whereof I have signed my name to this specification.

WALTER H. KIRKBRIDE.
